CLAIM

The ornamental design for a Halloween decoration, as shown and described.

DESCRIPTION

FIG. 1 is a perspective view of a Halloween decoration showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is an enlarged portion view taken from encircled portion labeled, "FIG. 9," in FIG. 1; and,

FIG. 10 is an enlarged portion view taken from encircled portion labeled, "FIG. 10," in FIG. 1.

The dot-dashed broken lines shown in FIGS. 1, 9 and 10 illustrate the boundary lines of the enlarged portion views of FIGS. 9 and 10 and form no part of the claimed design. The even dashed broken lines shown in the drawings represent portions of the Halloween decoration that form no part of the claimed design.

1 Claim, 10 Drawing Sheets
